UNITED STATES PATENT OFFICE.

WILLIAM F. ROBBINS, OF SCRANTON, PENNSYLVANIA.

AIR-COMPRESSOR.

1,147,646.

Specification of Letters Patent. Patented July 20, 1915.

Application filed May 15, 1914. Serial No. 838,726.

To all whom it may concern:

Be it known that I, WILLIAM F. ROBBINS, a citizen of the United States, residing at Scranton, in the county of Lackawanna and State of Pennsylvania, have invented certain new and useful Improvements in Air-Compressors, of which the following is a specification.

This invention relates to an air compressor and more particularly to a windmill driven compressor especially designed for house and factory use.

An object of the invention is the provision of a device of this character embodying an air compressor, tank and pressure controlled device for automatically closing communication between the compressor and tank when the air pressure in the tank exceeds a predetermined value.

Another object is the provision of automatically operated brakes for retarding and stopping the rotational movement of the wind wheel and the rotatable supporting frame thereof when the air tank is filled to its capacity.

With these and other objects in view, the invention consists in the novel construction, arrangement and combination of parts as will be hereinafter specifically described, claimed and illustrated in the accompanying drawings, in which—

Figure 1 represents a side elevation of the complete apparatus, Fig. 2 represents a vertical sectional view on the line 2—2 of Fig. 35 1, Fig. 3 represents a horizontal sectional view on the line 3—3 of figure, and, Fig. 4 represents an enlarged sectional view of the pressure controlled mechanism.

Referring to the drawing in detail, where-
40 in similar reference numerals designate cor-
responding parts throughout the several
views, the numeral 5 indicates a pair of an-
nular members concavo-convex in forma-
tion, said members being spaced and suit-
ably secured in spaced relation by the ver-
45 tically disposed bars 6. The frame consist-
ing of the bars 6 and annular members 5 is sup-
ported in elevated position by the in-
clined standards 8. Annular members 9 are
50 arranged above and below the upper and
lower annular members 5, respectively, and
are secured in spaced relation by the rods
10 suitably bolted at their opposite extremi-
ties to the annular members 9. The annular
55 members 9 are concavo-convex in cross sec-
tion, and provide a channel between the an-

nular members 5 in which balls 11 are dis-
posed. The lower ends of the inclined up-
rights or standards 8 are suitably anchored
in the ground and non-rotatably support the
bars 6 and the inner annular members 5, and
the annular members 9 and the rods 10 are
rotatable in the stationary frame.

A bearing 12 is secured to the upper face
of the inwardly directed plane portion 13
of the top annular member 9 and rotatably
supports a shaft 14 to the outer end of which
is secured a wind wheel 15. The opposite
end of the shaft 14 is rotatably mounted in
a socket 16 formed on the end of the stem
17 of the vane 18. A vertically disposed
shaft 19 is rotatably mounted concentrically
within the disks or annular members 5 and
9 and is rotatably supported in a suitable
bearing 20 secured to the lower annular or
disk member 9. A bevel gear wheel 21 is
fixed to the upper end of the shaft 19 and
meshes with a bevel gear wheel 22 secured
adjacent the inner end of the wind wheel
shaft 14.

A frame structure consisting of vertically
disposed legs 23 and horizontally disposed
side rails 24 is mounted below the wind
wheel and its coöperating parts and is pro-
vided at one end with a shaft 25 upon which
is fixed a bevel gear wheel 26 meshing with
a bevel gear wheel 27 fixed to the lower end
of the vertically disposed shaft 19. A pin
28 is fixed eccentrically in the inner face of
the bevel gear wheel 26 and is pivotally con-
nected with a pitman 29 connected with a
suitable cross head 30 reciprocable between
suitable guides 31 secured to the side rails 24
of the frame structure. The cross head 30
is connected with a piston rod 32 carried by
the piston 33 reciprocable within a cylinder
35 also secured to the side rails 24. The cyl-
inder 35 is provided with a suitable air inlet
port (not shown) and is adapted to force air
through a pipe line indicated generally by
the numeral 36 in Fig. 1. A suitable check
valve 37 is interposed in the pipe line 36 to
prevent air forced into the tank 38 from
finding its way back into the cylinder 35,
and a suitable manually operable cut-off
valve 39 is also provided in said pipe.

A cylindrical casing 40 communicates with
the pipe line 36 through a coupling 41, and
a piston 42 is mounted for sliding movement
within the casing 40 and carries a stem or
rod 43 having its upper end 44 bifurcated.
The lower portion of the casing 40 is pro-

vided with an aperture in which is secured one end of a pipe 45. A pipe 46 communicates with the tank 38 above the pipe line 36 and extends into the upper portion or dome 5 47 of a second cylindrical casing 48 in which is slidably mounted a piston 49 carrying a stem or rod 50 projecting through the lower end of the casing provided with a bifurcated end 51. A short pipe connection 52 connects 10 the medial portion of the cylinder or casing 48 with the pipe 45.

A supporting bracket 53 is secured in a vertical position above the side rails 24 of the frame structure and is provided with a 15 pin 54 on which is pivotally mounted a lever 55 secured at one extremity between the bifurcations 51 of the piston rod 50 and at its opposite end between the bifurcation 44 of the piston rod 43. The end of the lever 20 55 connecting with the piston rod 50 is normally retained in elevated position by the tension of a spring 57 disposed in a suitable casing 58 and bearing against the under side of a piston 59 carrying a stem 60 positioned 25 through the cap 61 and having pivotal connection with the lever 55 at 62 intermediate the pivotal mounting 54 of said lever and the pivotal connection between the end of said lever and the piston rod or stem 50. 30 The connection between the piston 59 and stem 60 is preferably adjustable whereby the force exerted by the spring 57 against said piston and the lever 55 may be adjusted as desired.

35 The pipe 45 into which the air escapes when the tank 38 is filled to capacity communicates with a cylinder 64 secured to the end of one of the side rails 24 and in which a piston (not shown) is slidably mounted 40 carrying a stem or rod 65 carrying at its upper end a brake shoe adapted to bear against the under face of the bevel gear wheel 27 to retard the movement of said wheel and the shaft 19. The pipe 45 also 45 communicates through a branch pipe 66 with a second cylinder 67 in which is slidably mounted a piston (not shown) carrying a rod or stem also provided with a brake shoe adapted to engage the under face of the bottom annular member 9 thereby preventing 50 the rotatable frame from being rotated by the vane when the wind wheel is not required for use supporting frame.

In operation, the wind wheel 15 is operated by the wind, rotating the shaft 14 and the shaft 19 through the bevel gear wheels 21 and 22, and rotating the horizontally disposed shaft 25 through the gear wheels 26 and 27. The movement of the bevel gear 60 wheel 26 is transmitted to the compressor piston 33 through the pitman 29 and piston rod 32, thus drawing air into the cylinders 35 and forcing it into the tank 38 through the pipe line 36 and valves therein. When 65 the pressure in the tank 38 exceeds a prede-

termined value, the air pressure in the pipe 46 forces the piston 49 downwardly within the cylinder 48 pressing the adjacent end of the lever 55 against the tension of the spring 57 and raising the opposite end of said lever, 70 thus raising the piston 42 in the cylinder 40. As the pistons 49 and 42 are moved past the open ends of the pipe 45 and branch pipe 52, the air pumped from the cylinder 35 is permitted to flow through the pipe 45 and is 75 conducted into the cylinders 64 and 67.

The air pressure in the last named cylinders forces the pistons therein upwardly frictionally engaging the brake shoes carried thereby against the bevel gear wheel 27 and 80 bottom annular member 9, thus effectively retarding and stopping the rotational movement of the wind wheel and rotatable supporting frame thereof.

What I claim is:—

1. In combination, a support, a frame rotatable in said support, a wind wheel rotatably mounted on said rotatable frame, a vane fixed to said rotatable frame, an air pump, driving connections between said wind wheel and said air pump, a storage tank, valved connections between said air pump and said storage tank, and pressure controlled means communicating with said tank for retarding the movement of said 95 rotatable frame.

2. In combination, a support, a frame rotatably mounted in said support, a wind wheel rotatably mounted on said rotatable frame, a vane secured to said rotatable frame, an air 100 pump, driving connections between said wind wheel and said air pump, a storage tank, a valved connection between said air pump and said storage tank, and pressure controlled means communicating with said storage tank for simultaneously retarding 105 the operation of said rotatable frame and said driving connections.

3. In combination, a support, a frame rotatable in said support, a wind wheel rotatably mounted on said rotatable frame, a vane fixed to said rotatable frame, an air pump, driving connections between said wind wheel and said air pump, a storage tank, a valved connection between said air 110 pump and said storage tank, a cylinder mounted under said rotatable frame, a similar cylinder mounted under said driving connections, a piston mounted in each cylinder, a piston rod secured to each piston, a brake 115 shoe secured to the free end of each piston rod, one of said brake shoes being adapted to engage said rotatable frame and the other being adapted to engage said driving connection, pressure controlling means communicating with said storage tank, and said cylinders whereby said brake shoes can be applied and the rotation of said rotatable frame and said driving connecting means is 120 stopped.

4. In combination, a support, a frame rotatable in said support, a wind wheel rotatably mounted on said rotatable frame, a vane fixed to said rotatable frame, an air pump, driving connections between said wind wheel and said air pump, a storage tank, a valved connection between said air pump and said storage tank, a cylinder mounted under said rotatable frame, a similar cylinder mounted under said driving connections, a piston mounted in each cylinder, a piston rod secured to each piston, a brake shoe secured to the free end of each piston rod, one of said brake shoes being adapted to engage said rotatable frame and the other being adapted to engage said driving connection, a cylindrical casing, a piston in said casing, a second cylindrical casing communicating with said pump, a piston mounted in said casing and normally seating

over said communication between the pump and casing, an air pipe connecting said second casing and said cylinders, a pivoted lever connecting said casings, an over-flow pipe connecting said storage tank and said first named casing, and being adapted to operate the piston in said casing when the pressure in said pipe exceeds a predetermined value whereby the piston in the second named casing will be unseated allowing air from said pump to flow through the pipe connecting the casings and the cylinders thereby raising said pistons in the cylinders and applying the brakes.

In testimony whereof I affix my signature in presence of two witnesses.
